TACKLE FOR FLAT KNITTING MACHINES

Frederick C. Good, Philadelphia, Pa.

Application November 25, 1936, Serial No. 112,650

13 Claims. (Cl. 66—127)

The present invention relates to the actuation of thread-bar-selector mechanism carried by friction boxes.

One purpose of the invention is to provide axially immovable operating mechanism normally disconnected from the friction box for actuating a movable thread carrier selector carried by the friction box and adapted to engage successive thread carrier bars.

10 A further purpose is to operate thread carrier selecting mechanism carried by a friction box from an actuator movable in a plane perpendicular to the direction of box movement while keeping the actuating mechanism from longitudinal movement.

15 A further purpose is broadly to adapt a thread rod carrier selector carried by a friction box to actuation by a transversely movable member as compared with a member movable parallel to the friction rod and to accommodate to this actuation a large range of types of selector carried by the box, whether the selector have the same or a different train of actuating mechanism at the two ends of the stroke of the friction box.

20 A further purpose is to offer a choice of connections by which a swinging bar may be utilized to actuate selector mechanism on the friction box, permitting origin of the movement either in a cam carried by the main cam shaft or for example by a pattern chain.

25 A further purpose is to provide an actuating mechanism shifting toward and from the friction shaft or rod or mechanism carried by the friction box as distinguished from that movable parallel with the friction shaft or rod, applying the actuating mechanism to movement of the same train of mechanism at each end of the friction box stroke or to individual trains of mechanisms operated at the different ends of the friction box stroke as preferred.

30 A further purpose is to actuate a star wheel for engagement with thread carrier bars or their attachments by means which is movable transversely of the axis of the main cam shaft as distinguished from means movable longitudinally with respect thereto.

35 A further purpose is to operate two star wheels independently at different ends of the stroke of a friction box and from a transversely movable swinging frame as distinguished from a device movable in the general direction of movement of the friction rod.

40 A further purpose is to operate selector fingers by cams carried by the friction box, rotating the cams by means normally disconnected from the

cams movable transversely of rather than parallel to the friction box at the time of actuation.

45 A further purpose is to use either a single selector star wheel or two selector star wheels which engage with parts carried by individual thread carrier bars in connection with transversely movable actuating means which is not movable longitudinally of a full fashioned machine.

50 A further purpose is to connect a selector-operating ratchet wheel and its shaft carried by a friction box with actuating mechanism moved by the main cam shaft or by a pattern wheel and not movable longitudinally with respect to this shaft.

55 Further purposes will appear in the specification and in the claims.

The invention relates not only to the mechanism shown but to methods or processes disclosed.

The preferred mechanisms are shown in the 20 accompanying drawings in which:

Figure 1 is a transverse sectional elevation of a sufficient portion of a full-fashioned hosiery knitting machine to illustrate the application of the mechanism of the present invention thereto. 25

Figure 2 is a plan view of the mechanism shown in full lines in Figure 1 and looking from the rear of the machine in the direction of the arrow 2 in said Figure 1.

Figure 3 is a transverse sectional elevation or 30 end view of the same.

Figure 3a is a fragmentary elevation of a thrust member seen in Figure 3.

Figure 4 is a longitudinal sectional elevation taken on line 4—4 of Figure 3. 35

Figures 5, 6, and 7 inclusive are cross sectional details of various parts of the mechanism illustrated in Figures 2, 3, and 4.

Figure 8 is a detached perspective view of the carrier bar selecting and driving or coupling elements. 40

Figures 9 to 19 inclusive are diagrammatic plan views of three of the carrier bars of the machine, illustrating the sequence of operations of the carrier bar selecting and driving elements. 45

Figures 20 to 25 inclusive are diagrammatic views of the carrier bar selecting and driving elements in the various positions assumed in selecting and operating the carrier bars in the manner shown in Figures 9 to 19 inclusive. 50

Figure 26 is an end elevation showing the old parts in dot and dash and illustrating actuating mechanism with the selector seen in the preceding figures. 55

Figure 27 is a side elevation showing the actuating mechanism alone.

Figure 28 is a top plan view of a part of the actuating mechanism.

5 Figures 29, 30, 31, 31b, 32 and 33 are end elevations, some on reduced scales, of actuating structures of the general type shown in Figure 26.

10 Figure 31a is a fragmentary longitudinal section corresponding to line 31a-31a in Figure 31.

Figure 34 is a top plan view of one of the many types of selector mechanism to which the present invention may be applied.

15 Figure 35 is a fragmentary section upon line 35-35 of the structure shown in Figure 34 showing application of the actuating mechanism of any of the preceding figures to the selector of Figure 34.

20 Figure 36 is a fragmentary cross section of a part of the structure of Figure 34 including matter not shown in that figure.

25 Figure 37 is an end elevation and partial section showing application of my actuator to still another form of selector mechanism carried by friction boxes.

Figure 38 is a fragmentary top plan view of the structure of Figure 37.

30 Figures 39 and 40 are a sectional elevation and top plan, respectively, of another form of the invention.

In the drawings similar numerals indicate like parts.

35 In the operation of full-fashioned knitting machines threads are knitted such as silk which are not of uniform thickness or diameter but which instead have relatively thick and relatively thin places occurring at different stretches of their lengths.

40 In handling such threads of variant thickness it is quite desirable to avoid the laying of courses of either thick or thin thread successively to any considerable extent with the result that various mechanisms have been proposed for laying successive courses from different thread sources, 45 normally requiring that at least three thread bars shall be used during this part of the knitting and that the corresponding carrier bars shall be operated sequentially according to a predetermined order. The operation of "striping" also requires 50 the engagement of different bars successively, even though there may be as few bars as two in the succession and each bar may be used to lay thread in many successive courses.

Various constructions providing for selection 55 and engagement of the carrier bars in a proper order for three bar operation have been manufactured and used which are carried by the friction box and which are actuated after the friction box completes its stroke, either from some 60 member movable longitudinally of the machine, in correspondence with the travel of the friction box, such as from a slur bar or which are actuated from a cam shaft.

65 The present invention comprehends a plurality of actuators of widely different characters for selectors of several varieties which have been manufactured and used and the actuators are adapted to be applied to any type of selector which is carried by a friction box and which 70 progressively and selectively engages, carries and disengages from different thread carrier-bars so as to lay the corresponding threads in courses, one after the other according to a predetermined system.

75 The first illustration of the preferred actuator

in connection with a selector applies it to applicant's three-carrier-selector mechanism upon which application has been filed, Serial No. 49,087, filed November 9, 1935. Figures 1 to 25 of this application, Serial No. 49,087, are the same, except for the actuator and omission of a safety device, as the correspondingly numbered figures of the present case. Taking then the first twenty-five figures, the structure shown is intended to operate three different threads in such sequence 10 that the courses from these threads shall be laid in turn, one course from each, repeating to produce a so-called ringless effect.

15 Each thread is controlled by an individual thread carrier bar. The mechanism for selecting the individual bars in turn and engaging them to lay the threads is the same in Figures 1-25 as in my former application.

20 In order to illustrate the fact that my mechanism is of broader scope than would be represented by actuating my earlier selector mechanism merely and is suited to operation of other mechanism I have illustrated in Figures 34-38 mechanisms which have been made and which have gone into public use along with various actuating 25 means.

25 In Figure 1 the main parts of a conventional full-fashioned hosiery machine are shown in dot-and-dash with full line illustration of parts showing the selector and the actuator therefor. The cross frame appears at 11, the back center bed at 12, and one of the brackets for a back narrowing shaft 13 appears at 14.

30 This bearing bracket is extended at 15 to support friction box drive rod 16. There is also support from the extension 15 for a friction box guide rod 17 extending parallel to the drive rod 16 throughout the length of the machine. The slur cock bar 18 is shown in order to point out the position of other parts in the present invention but is not used for selector actuating purposes.

35 The usual thread carrier bars 1 to 8 inclusive are carried by the back center bed 12 through brackets 19 having transversely extending heads 40 20. The friction rod 16 and slur cock bar 18 are reciprocated by the usual Coulier motion, not shown.

45 The various thread carrier bars are reciprocated by a series of friction boxes having slides 50 or arm connecting with the bars so that the various friction boxes will receive longitudinal reciprocation and the threads may be laid to the needles and interlooped courses of stitches may be made. The bars are limited in movement 55 by end stops, not shown.

50 For selective driving of any of three carrier bars a special friction box 25 is used mounted in the usual manner and provided with the usual friction leathers carried by the usual shoes 60 adapted to be connected to or loosened from the drive rod by movement of the handle 26 in the usual manner.

55 Secured to each of the opposite ends of the friction box 25, as illustrated, is a split collar. 65 These appear at 27 and 28. These collars are mounted on circular axial extensions 29 of the friction box 25 and are clamped in definite position thereon by tap bolts 30, 30. The collars 27 and 28 are provided with forwardly extending 70 arms 31 and 32 respectively. Mounted in the arms 31 and 32 and projecting inwardly toward each other are sleeves or bushings 33 and 34 respectively. Within these sleeves or bushings 75 is a hollow shaft 35 and as more clearly illus-

trated in Figure 4 upon the shaft 35 at the center and between the arms 31 and 32 are two laterally (axially) spaced wheels 37 and 38 which resemble star wheels and which function as selectors and driving or coupling elements for the three carrier rods, 1, 2, 3, as shown in Figures 1 and 3.

The wheels 37 and 38 are respectively carried by and fixedly secured to hub members 39 and 40 respectively. Integral with or connected to the hubs 39 and 40 respectively are ratchet wheels 41 and 42. Index wheels 43 and 44 are also secured to the hubs 39 and 40.

Detent brackets 45 and 46 (see Figure 4) are fixed to or formed integral with the inner ends of the sleeves 33 and 34 respectively, each of which brackets is provided with a radially extending cylindrical portion, seen at 47 and 48. As seen in Figure 6 each of these cylindrical extensions is provided with a bore 49 in which detent plunger 50 slides. Between the plunger and the outer screw plug 51 closing the outer end of the bore is a spring 52 by which the detent 50 is yieldingly pressed and held within one of the peripheral notches 53 of the index wheels 43 and 44.

The sleeves 33 and 34 and detent cylinders 47 and 48 carried thereby may be adjusted axially of the friction rod and also angularly for the purpose of registering the selecting or coupling wheels 37 and 38 with respect to the carrier rods 1, 2, and 3. The sleeves then are locked in adjusted position by set screws 55 and 56 which are threaded into the arms 31 and 32 as shown in Figure 2.

The opposite ends of the hollow shaft 35 are provided with nuts 57 and 58 respectively which bear against the outer ends of the sleeves 33 and 34 respectively, whereby wear and axial play between said sleeves and the selector wheel hub elements 39 and 40 may be taken up.

The shaft 35 (see Figure 4) is perforated radially and circumferentially grooved as indicated at 59 and 60 to provide for lubrication of the various working elements mounted on said shaft, said lubrication passing through the hollow center of the shaft 35 from any suitable grease or oil supply (not shown) but which may be connected to the threaded ends 61 and/or 62 of the shaft 35, said lubricant passing through the perforations 59 into the grooves 60 and distributing along the outer operating surface of the shaft 35.

Mounted for oscillation on the sleeves 33 and 34 respectively, between the arms 31 and 32 and the detent brackets 45 and 46 are the hubs 63 and 64 of pawl carriers which include arms 65 and 66 formed integral with the hub 63 and 64 and having extensions projecting axially over the end of said hubs across the detent wheels 43 and 44 and ratchet wheels 41 and 42.

The sleeves 33 and 34 may be perforated to permit lubrication for the pawl carrier hubs 63 and 64 from the hollow shaft 35.

Pivotaly mounted on the ends of the overhanging portions 67 and 68 of the pawl carrier arms 65 and 66 are pawls 69 and 70 which co-operate with the ratchet wheels 41 and 42 respectively for moving the carrier rod selector wheels 37 and 38 alternately and step-by-step as will be more fully disclosed hereinafter.

Each of the pawls 69 and 70 is pressed against its ratchet wheel by flat spring 71, one end of which presses against the pawl and the other 75 of which is clamped in extension 67 or 68 of

the pawl carriers 63 or 64 by means of clamp plates 72.

Two main distinctions are to be noted as between the slur-actuator for the selector in the former application and the present actuator 5. The actuator here takes its movement from a rotary and not from a longitudinally movable member. The movement of the actuator is in a direction transverse to the direction of movement of the friction box and not parallel thereto. The selector shown in this form of Figures 1 to 8 is a transversely swinging bar operated from a rotary cam which may be and here is mounted upon the main cam shaft. It is wholly free from support by the friction box and extends throughout a range sufficient to engage the selector mechanism at both of the limits of friction box travel and whatever limitation of friction box travel may be effected by the narrowing mechanism. So far as the operation of the transversely movable bar is concerned it can be made to operate from a main cam in that one of the two longitudinally shiftable positions of the main cam shaft in which knitting takes place (i. e. as distinguished from the shaft position when narrowing takes place). It can be rendered inoperative when desired by throwing the selector device out of reach of the actuator bar just as in the case of my prior application. This is later described.

The present form of actuator is not dependent upon the continued movement of any of the reciprocating parts but of course does not come into operation for a new course until the last preceding bar carried by the selector has come to rest.

The actuating device carries two presser faces 73', 73² (Figures 1 and 4), for engagement with mechanism carried by the selector, i. e. movable with the friction box. Because the mechanism carried by the friction box requires to be differently actuated at the two ends of the friction box stroke these two presser faces are not parts of a continuous surface but are separated. It is desirable that they be connected for added strength. This is here accomplished by merely spacing them at opposite ends of a recess 73³ so that either one of the mechanisms may be free from actuation while the other is being actuated. The two presser faces need not be connected. In the drawings, for convenience the two presser faces are 40 connected by a single presser plate or bar 73 with which the surfaces 73' and 73² are effectively connected.

The presser plate or bar 73 is operated by a lever arm 74 (Figures 27 and 28) which may be 55 a single arm but which for greater stiffness is constructed as a composite, shown as made up of side strips 74' and 74² and intermediate braces 74³. The lever arm is mounted upon any suitable pivoting bracket 75 by means of pivot 60 rod 75'. The position of the bracket will, of course, depend upon the position of frame parts or other parts in the individual machine to which the invention is applied.

The arm 74 is limited in its release movement 65 in any suitable manner as by extensions 74⁴ beyond the pivot (Figures 26 and 27) and by the adjusting limiting screws 74⁵ with which the extensions engage.

The lever arm 74 is pulled to operating position 70 through link 76 by a swinging lever arm 77 forked to carry roller 77' engaged by a cam 78² upon any suitable cam wheel 78'. In the illustration the cam wheel is mounted on the main cam shaft 78, which is more convenient than 75

would be the use of a separate shaft and is also economical of space. Other ways of operating an actuator than by a wheel cam (as for example, by a pattern chain) and other types of actuator than a swinging arm (as, for example, Figure 39) will occur to the designer familiar with this art.

Suitable pivots 75², 75³ connect the link 76 with the arms 74 and 77 respectively and the arm 77 is pivoted in bearings 75⁴ mounted on any suitable bracket 75².

The entire actuator can be rendered inoperative merely by sliding the lever arm 77 along pivot 75⁴ so that wheel 77 will ride upon the circular part of cam wheel 78' and will not be engaged by cam 78² with shifting of the main cam shaft. The cam wheel 78' may be made wide enough to accommodate this shift for purposes of preventing actuation of the selector where the selector cannot itself be wholly disconnected. This then permits the particular bar with which the selector was last connected to be operated all the time by the friction box.

The lever 74 is held normally and resiliently in position by any suitable spring 103 at one end secured in the link 76 and at the other end fastened at any suitable point which may be a fixed point connected with the bracket 75.

It will be noted that the cam 78² can be of any type suited to actuate the lever arm 74 and operate the presser feet according to any predetermined plan.

Alternate step-by-step rotation of the selector and driving wheels is attained by action of the presser faces 73' and 73² against rollers 81 and 82 mounted on the lower ends of levers 83 and 84. The levers are pivotally mounted on the pivot 85 supported by lugs 86 and 86' formed on the collars 27 and 28 respectively.

The opposite ends of the levers 83 and 84 are connected by links 87 and 87' to levers 88 and 88' formed on or carried by the hubs of the pawl carriers 63 and 64 respectively, so that when reciprocation of the friction box to the left in Figure 4, for example, brings the lever 83 in line with presser face 73', the roller 81 will be engaged by the presser face and will be pushed forward (Figures 4 and 26) but the roller 82 will pass within the recess 73³ and will not be actuated.

When movement of the friction box has brought it to the end of its stroke at the right in Figures 4 and 26, forward movement of the presser bar will cause its presser face 73² at this end of the bar to engage roller 82 and push lever 84 forwardly, whereas roller 81 will be in line with that part of the presser bar which is recessed at 73³ and roller 81 will therefore not be engaged and will thus not be actuated.

On the other hand it will be noted that presser faces 73' and 73² form the engaging devices, impellers or drivers on the part of the actuator which connect with and transmit motion to levers or other devices carried by the friction box to effect the selector function. The levers or other devices 83 and 84 in the present instance are the first of the train of selector mechanism which moves with the friction box and for the present purpose are viewed as the friction box-carried operating members or levers. It will be noted that the actuator impellers or drivers 70 and the selector operating members constitute the transfer mechanism by which movement of the actuator which is not lengthwise of the machine is transmitted into movement of the selector which travels lengthwise of the machine.

75 The impellers or drivers having presser faces

73' and 73² are long enough each of them to insure engagement of the corresponding impeller or driver with the roller 81 or the roller 82, as the case may be according to the end of the stroke at which engagement takes place, notwithstanding that the narrowing operation causes the roller 81 and the roller 82 to stop at different positions throughout the range of narrowing which is provided, and the space between the presser faces 73' and 73² is sufficient so that what might be termed the lagging roller 81 or 82 according to the last direction of movement of the friction box will reliably fit into the space between and will not be operated by the actuator bar.

Each engagement of one of the presser faces with roller 81 or 82 upon lever 83 or 84—according to the end of the stroke at which the friction box has come to rest—rotates the corresponding selector wheel sixty degrees about the axis of the shaft 35 and through a train of connections now to be described.

The links 87 and 87' are joined to the levers 83 and 84 respectively by longitudinally separable yokes 88⁴ and pins 88⁵ so that the links and the levers would be separated but for springs 89 connected between the pins 89' upon the hubs 63 and 64 to which the links are connected, and the pins 89² upon the levers 83 and 84.

The springs serve two functions. The one is to permit lost motion in the tensional movement of the levers so that the star wheels 37 and 38 will not be forced against the dogs when they are not free to turn across the faces of the dogs. Instead the lever 83 or 84 moves, stretches the associated spring and opens the lost motion joint between the parts 88⁴ and 88⁵. The other purpose is to draw the levers and links back to their initial position after the lever 83 or 84 has been moved to actuate the corresponding star wheel.

As shown in Figures 5, 6, 8 and 20 to 25 inclusive, the selector wheels 37 and 38 are of the general hexagonal contour, and, as shown in Figures 1 and 3, the axis of rotation of these wheels is above and substantially in the plane of the center of carrier bar No. 2.

Each of the carrier bars 1, 2 and 3 is provided with a driving dog, 1a, 2a and 3a respectively, said dogs being of a length substantially equal to the distance between the inner opposed faces of the selector driving wheels 37 and 38 with just sufficient clearance between the ends of the dogs and the inner opposed surfaces of the wheels to allow for the rotation of one of the wheels, the leading wheel relative to the dog when the trailing wheel in the direction of friction box movement is pressing the dog in the direction of the last movement. However, at such time as any one of the dogs is positioned between the opposed surfaces of said wheels to connect the carrier bar to the friction box 25 for driving movement of the carrier bar, this clearance is not sufficiently great to allow any appreciable amount of relative longitudinal movement of the bar with respect to the wheels between which the dog is gripped, thus providing for accurate controlling and positioning of the carrier bars with respect to the needles and sinkers of the machine at the ends of the respective strokes of the carrier bars.

Each of the wheels 37 and 38 is provided with a pair of diametrically opposed radial dog-clearing notches or openings 37a, 38a, formed in opposed parallel perimeter surfaces 37b, 38b of said wheel, and diametrically opposed radial dog-clearing notches or openings 37c, 38c disposed at right

angles to the dog-clearing notches 31a, 38a and located at corners formed by the intersection of two adjacent perimeter surfaces 31b, 38b of the hexagonal wheel, which provides a plurality of 5 solid dog-engaging portions or lugs 31d, 38d alternating with the surfaces and corner dog-clearing notches or openings 31a and 38a.

Normally one of the surfaces 31b and 38b of the wheels 31 and 38 lies in a plane parallel to 10 and spaced above the plane of the top surfaces of the carrier bars 1 to 8 inclusive, as illustrated in Figures 1 and 3, and one of the dog-engaging lugs 31d or 38d of one of the wheels 31, 38 is at all times in overlapping relation to one of the 15 lugs of the other wheel and one of the dog-clearing spaces adjacent thereto, as will be clear in the following description of the operation of said wheels.

It will be understood that each of the carrier 20 bars 1, 2, 3, etc. is provided with a number of thread guides, one for each knitting head in the machine, and when the driving dogs of the carrier bars are positioned at the left, as seen in Figure 9, the thread guides carried by such bars 25 are disposed at the left hand selvage of each stocking or other piece of fabric being knit, as determined by the left hand end stops of the machine; and that when the driving dogs are at the right hand end (as seen in Figures 10 and 11) 30 the thread carriers on those particular bars are disposed at the right hand selvage of each stocking or fabric piece being knit, as determined by the right hand end stops of the machine.

Figure 9 illustrates the dogs 1a and 3a of the 35 bars 1 and 3 respectively at the left hand side and the dog 2a of the bar 2 at the right hand side. Figure 20 illustrates the relation of the wheels 31 and 38 as viewed from the left in Figure 9. One of the dog-engaging lugs 31d of the wheel 31 is in engagement with the left hand end 40 of the dog 1a of the bar 1, and extends across the carrier rod 2, one of the corner dog-clearing openings 31c being aligned with the dog 3a of the bar 3. One of the dog-engaging lugs 38d of the wheel 38 is disposed at the opposite side 45 of the dog 1a of the bar 1 and another of the dog-engaging lugs 38d of the wheel 38 is disposed at the corresponding side of the dog 3a of the bar 3 with a median dog-clearing opening 38a between said lugs disposed in alignment with the bar 2.

Taking the set-up of Figure 9 as a starting point in the cycle of operations of the wheels 31, 38 and bars 1, 2 and 3, the first movement of the 55 friction box 25 would be to the right, as indicated by the arrow in Figure 9. The dog 1a of the bar 1 being held between the wheels 31 and 38 would be correspondingly moved to the right from the position shown in Figure 9 to the position shown 60 in Figure 10, wherein the portion of the lug 31d of the wheel 31 which overlaps the dog-clearing opening 38a of the wheel 38 comes in contact with the inner end of the dog 2a of the bar 2, insuring that said bar is in contact with the 65 right hand end stop of the machine and properly aligned with and between the wheels 31 and 38. As above noted in Figure 9, one of the median dog-clearing openings 38a of the wheel 38 is aligned with the carrier bar 2 so that in the 70 movement of the wheels 31 and 38 from the position shown in Figure 9 to that shown in Figure 10, the wheel 38 is enabled to pass the dog 2a on the carrier bar 2 and thereby permit the dog to be engaged by the lug 31d of the wheel 31 as noted.

75 With the wheels in the position shown in Fig-

ures 10 and 20 and the bars 1 and 2 against the right hand end stop of the machine, transverse movement of the presser face 13² effects a one-step rotation of the wheel 38 from the position shown in Figure 20 to that shown in Figure 21, while the 5 wheel 31 retains its position shown in Figures 9 and 20, whereby the lug 38d moves out of alignment with the dog 1a into alignment with the dog 2a and extends over the bar 3, as illustrated in Figure 11, one of the corner dog-clearing openings 38c moving into alignment with the right hand end of the dog 1a.

The friction box drive rod 16 and the friction box 25 then move simultaneously to the left, as indicated by the arrow in Figure 11, the dog 15 2a of the bar 2, being held between the solid lugs 31d and 38d of the wheels 31 and 38, respectively.

The wheels move with the friction box 25 in the direction of the arrow 11, from the position shown in Figure 11 to the position shown in Figure 12. During this shift to the left the corner dog-clearing opening 31c of the wheel 31 clears the dog 3a of the bar 3 and the solid portion or lug 38d of the wheel 38, which is overhanging the bar 3, engages the inner or right hand end of 25 the dog 3a of the bar 3, moving the said bar and the bar 2 into contact with the end stops at the left hand end of the machine and aligning the dogs 2a and 3a with each other and with and between the wheels 31 and 38 for a subsequent 30 rotary shifting of the wheel 31 by the transverse movement of presser face 13² after the carriers 2 and 3 have engaged with the left end stops of the machine.

The wheel 31 during the last-mentioned rotary 35 shifting thereof moves from the position shown in Figures 12 and 21 to the position shown in Figures 13 and 22, while the wheel 38 retains its position of Figure 21. This shifting of the wheel 31 aligns one of the median dog-clearing openings 31a with the left hand end of the dog 2a of the carrier bar 2 and moves one of the adjacent lugs 31d into alignment with the left hand end of the dog 3a and the other of the adjacent lugs 31d into alignment with or overhanging 45 relation to the carrier rod 1, as shown in Figure 13.

The next movement of the friction box drive rod to the right moves the carrier bar 3 to the right from the position shown in Figure 13 to 50 the position shown in Figure 14, after which the wheel 38 is shifted from the position shown in Figure 21 to that shown in Figure 23, bringing a solid lug 38d into alignment with the dog 1a and overhanging the bar 2 with one of the dog-clearing openings 38c in alignment with the dog 3a of the bar 3.

The wheels 31 and 38 when next moved by the friction box 25 to the left, as illustrated in Figure 15, carry the dog 1a and the bar 1 from 60 the position shown in Figure 15 to that shown in Figure 16, wherein a lug 38d of the wheel 38 contacts the inner end of the dog 2a and moves the bars 1 and 2 into contact with the end stops at the left hand end of the machine and aligns 65 the dog 2a with the dog 1a for a shift of the wheel 31.

The wheel 31 then shifts from the position shown in Figure 22 to that shown in Figure 24 which causes a lug 31d of the wheel 31 to align 70 with the left hand end of the dog 2a and to overhang the bar 3, an opening 31c in the wheel 31 being brought into alignment with the dog 1a of the bar 1.

The friction box 25 and consequently the 75

wheels 37 and 38 then move to the right, as indicated in Figure 17, from the position shown in Figure 17 to that shown in Figure 18. After arriving at this position, the wheel 38 is again shifted from the position shown in Figure 23 to that shown in Figure 25, causing one of the lugs 38d to move into alignment with the right hand end of the dog 1a and another lug 38d to move into alignment with the bar 1 and positioning one of the openings 38a in alignment with the right hand end of the dog 2a.

The friction box 25 and wheels 37 and 38 next move to the left as indicated in Figure 19, carrying the dog 3a and the bar 3 from the position shown in Figure 19 to that shown in Figure 9 for a repetition of the cycle.

From the above, it will be clear that the thread carrier bars 1, 2 and 3 are moved successively in a predetermined order so that the threads controlled thereby are laid to the needles of the knitting machine once in the formation of each three courses of stitches in the single or several fabrics being made on the machine.

From the above description, it will be clear also that the carrier bars are under definite control of the wheels 37 and 38 at the time the selection is made and during the full stroke of each bar after it is selected for laying thread to the needles.

As previously noted, the friction boxes of flat knitting machines, particularly those employed in the making of full-fashioned hosiery, are held in definite relation to the bars 1 to 8 inclusive against rotary motion about the axis of the friction box drive rod 16 by a yoked lug on each of the friction boxes embracing a guide rod 17 which, as noted, extends parallel to the drive rod 16. In the present instance, and in order to provide operating space for the special friction box 25, one section of the guide rod 17 between a pair of the supporting brackets 15 is removed and a special guide rod 17a provided in offset relation to the rod 17. The special section 17a is supported from and by the ends of the rods 17 or by the brackets 15 through supplementary brackets 17b.

As shown in Figures 1 and 2, the friction box 25 is provided with a pair of rearwardly extending arms 91 and 92 respectively. These arms or a single arm may be carried directly by the body of the friction box 25, or, as in the present instance, the arms 91 and 92 are provided with shoulders 93 which engage the under side of the guide bar 17a and thus prevent the weight of the mechanism disposed over the carrier bars 1 to 8 from effecting a rotary movement of the friction box 25 about the axis of the drive rod 16, thus maintaining a pair of the flat perimeter surfaces 37d, 38d of the wheels 37 and 38 respectively in the above-noted parallel relationship to the plane of the upper surfaces of the bars 1 to 8.

In order to prevent upward movement of the wheels from the carrier bars in the present instance, the arm 92 slidably supports a latch 94 which projects outwardly over the upper surface of the guide bar 17a, as clearly shown in Figures 1 and 2.

The thread carrier bars 1, 2 and 3 are thus moved successively in a predetermined order so that the corresponding threads are laid, one course of thread from each bar being laid in turn, repeating the operation over and over again in each of the positions at which knitting takes place.

The carrier bars are under full control of the star wheels 37 and 39 since each lug on a carrier bar is at the time of movement of the bar held definitely between the two wheels. Moreover, at each end of the stroke the rear wheel—which may be considered the driving wheel—not only presses the lug of the bar which has just been moved tightly forward but engages the lug of the bar which previously has rested at that end of the stroke, pressing this carrier bar also in the direction of last wheel movement and holding the two bars in position while the other star wheel which has been the leading wheel during the last movement rotates to a new position without need of frictional engagement with the lugs of these two bars. With the reversal of movement of the friction box the previously leading star wheel becomes the driving star wheel, driving the bar which has previously been left at that end of the stroke and leaving the bar which has just been delivered. This reverse movement of the star wheels causes the star wheel which was the driving wheel to become the leading star wheel. It is turned to a new position at the end of its reverse stroke while the two bars whose lugs are located at this end of the stroke are held in position by the then-driving star wheel.

At each end of the stroke the lever 83 or 84, whichever it is, which operates the latch to turn the leading star wheel for that stroke, comes into position to be engaged by one or other of the presser faces 73', 73² while the other of the levers rests within the recess between these presser faces; with the result and effect that the leading wheel is shifted in position while the then driving star wheel holds the lugs tightly pressed in the direction of last movement, taking up any lost motion which there may be in the narrowing heads or other mechanism.

If at any time it is desired to use the carrier bars 1, 2 and 3 in the ordinary manner, that is, without selective operation thereof, the friction box 25 and all of the selecting mechanism carried thereby may be rotated upwardly about the axis of the rod 16 by retracting the latch 94, after which, release of the latch and subsequent projection thereof would cause the upper surface of the latch to engage the under surface of the guide bar 17a, thus retaining the wheels 37 and 38 in an elevated inoperative position. By this movement of the friction box 25, the cam followers 81 and 82 are likewise swung out of alignment with the cam 77 to an inoperative position.

Retraction and projection of the latch 94 is effected in the following manner:

The latch is slidably mounted in a guideway 95 formed in the arm 92 and is provided with a laterally extending pin 96 which projects through an elongated slot 97 formed in the side of the guideway 95. The outer projecting end of the pin 96 is engaged by one end of a lever 98, the opposite end of said lever being in the form of a handle 100 projecting outwardly over the top of the friction box 25. The lever 98 is pivotally mounted at 99 between a pair of lugs 101, 101 formed on the split collar 28, and a spring 102 having one end connected to the lever 98 and its opposite end connected to the split collar 28 tends to maintain the latch 94 in its projected state at all times.

In Figure 29 is shown a construction somewhat similar to that of Figures 26, 27 and 28 but with the difference that an operating wheel 77² is operated directly from a cam depression 78³ occupying part of the length of a cam wheel 78⁴, the 70

remainder of whose length is of uniform diameter throughout, so that the wheel 77² may ride upon the full diameter when the cam wheel 78⁴ is in a position corresponding with the narrowing position of the main shaft but will be acted upon by the cam depression 78³ in knitting positions of the main shaft. The shaft indicated at 78 is the main cam shaft of the machine but may be another shaft shiftable with it.

10 In this illustration of Figure 29 the extension 104 is much greater than that of 74⁴ in Figure 26 in order that this extension may not act as a stop only but may be used in a knocker function for operation of the lever 74⁶. The extension 104 is provided with a suitable wear plate 105 to be engaged by the end 106 of a lever 107 pivoted at 108 in a hanger 109 supported from any suitable fixed part of the machine. The lever 107 is bifurcated at 110, as lever 77 in Figure 26, in order 20 that the wheel 77² may be pivoted in it at 111, corresponding in this particular also with lever 77.

The wheel 77² is held in engagement with the surface of the cam wheel 78⁴ by a spring 112 so as to follow the contour of this wheel including—in proper longitudinal position of its shaft—dipping into the depression cam 78³.

Each movement of the wheel 77² into the depression cam 78³ gives an impulse to the lever 30 74⁶ to shift it in the direction of the arrow. This lever may be of the character seen in Figure 26 or of any other character suited to giving an impulse to the proper engaging member of a friction-box-carried selector.

35 The extension (heel) 104 is held in normal engagement with the end 106 by means of a spring 113.

In Figure 30 a more direct actuation is seen for a similar construction. The extension 104' engages the end 106' of a lever 107' pivoted at 108' in a swinging arm 114 pivoted at 115 in a support 109' mounted upon any suitable fixed part.

The lever 107' is forked at 110' to carry a wheel 77³ which is engaged by a cam 78², for example 45 upon the surface of a cam wheel 78¹. The wheel and cam including the shaft 78 may be a duplicate of the corresponding wheel and shaft in Figure 26; and if the shaft be the main cam shaft the cam projection 78² will extend for a part only of 50 the axial length of the surface of the wheel 78¹ so that the wheel 77³ will not be actuated during narrowing operations. The heel of the lever is held in engagement with the end 106' by means of a spring 113. Because of the objection to having lever 107' float unduly, the end of the lever is held in engagement with flange 116 by a spring 117 attached to the lever at one end, and whose point of attachment at the other end is not shown. This point of attachment may be any suitable 55 fixed part.

In Figures 31, 31a and 31b are shown alternative constructions in which a pattern chain may be used instead of the cam wheel 78¹ with its cams, as for example 78² or 78³.

60 The use of a pattern chain offers not only convenience in initially arranging what may be an odd timing or order of actuation but permits change of the timing subsequently. It is suitable for use in the same machine, for example, alternatively on three-thread bar actuation in sequence or for ring formation. This would permit either ringless or knitting in which failure to protect against rings may result in rings appearing upon the same machine as well as of course 65 the ordinary knitting when the selector mecha-

nism is thrown out of position to engage the thread bars. With the "ring" knitting, a number of successive courses of thread from the same thread source can be supplied, while with the three thread bar selection a single course from each source, successively, can be supplied.

In Figure 31 the cams upon the pattern chain are applied to the operation of a lever 74⁷ having an extension 104² provided with wear strip 105 in position to be engaged by the cams 118, 118¹, 118², 118³ at whatever spacing may be desired. The lever is returned by a spring 113.

The pattern chain 119 passes about a driving sprocket wheel 120 which may be driven by the main cam shaft 78, and over an idler sprocket wheel 121, the idler being in position to support the cam while it is giving impulse to the heel 104² of any suitable lever 74⁷. The illustration is suitable for use when the shaft shown is the main cam shaft. The driving wheel 120 is free to 20 rotate about the shaft 78. Normally, shifting of the main cam shaft will throw a clutch 122 pinned upon it at 123 into engagement with the cooperating clutch member 124 rigid with the driving wheel 120. The cooperating clutch member and wheel 120 are held in position along the length of the shaft by a strap 125. The strap is arranged to be positioned by a fixed member 126 by either of two sets of fastenings 127, 128. When positioned by fastenings 127 the clutch member 30 will engage whenever the main cam shaft is in knitting position, but will be disengaged when the main cam shaft and the clutch member 122 carried by it shift longitudinally to narrowing position. When the strap 125 is positioned by fastenings 128 the entire pattern chain is rendered inoperative, as the clutch members cannot engage in any longitudinal position the main shaft.

In Figure 31b the structure is or may be substantially the same as in Figure 26 except that the driving wheel 120 acts as a support for the cams upon the pattern chain while they are engaging with heel 77 upon swinging lever 77, by which the lever 74 is actuated through link 76. The wheel 121 thus becomes an idler only to stretch the pattern chain and does not act as a support for cams while they are engaging any part of the operating lever.

The illustrations of the forms of Figures 31, 31a and 31b are intended to indicate the flexibility of the pattern chain substitution form for a wheel cam form in any location where a cam can be used. It is not considered necessary to extend further the showing that the pattern chain construction can be substituted in other forms.

In Figure 32 a pattern chain of the same type as shown in Fig. 31 is intended to be driven in the same way by a drive which is clutched with knitting position of the main cam shaft, free when the main cam shaft is in the narrowing position and capable of being released altogether. This is applied to a swinging arm of the general type seen in Figure 26, there being much in common with the structure of Figure 26 but with substitution of the chain for the cam wheel of Figure 26.

In this Figure 32 the chain cam during its operation is sustained by the wheel 121 which is an idler whereas in Figure 31b the cam during operation is sustained by wheel 120 which with respect 70 to the chain is a driving wheel.

In Figure 33 is illustrated a different form of main cam shaft actuation which operates in a direction transverse to the direction of movement of the friction box but in which the actuator in 75

making engagement with a selector member does not have horizontal or nearly horizontal impeller movement.

In common with some of the other figures it uses a cam 78² on a cam wheel 18' driven by the main cam shaft 78 with some provision for continuance of engagement of roller 77³ with the surface of wheel 18' alone in the position of the main cam shaft during narrowing operations and 10 of engagement by the cam 78² when the main cam shaft is in position for knitting operations. The link 126 is supported and guided by anti-friction wheels 127 at one end and at the opposite end at 128 is pivoted to a rocker arm lever 15 129 pivoted at 130 in a fixed support.

The other arm 129' of the rocker arm is slotted at 129² and is pivoted within the slot to a vertically movable thrust rod 131 guided between anti-friction wheels 127 so as to lift and 20 lower with movements of the link 126. The thrust rod is shown as fixed against movement parallel to that of the friction rod and is wholly free from the friction box except as it momentarily engages and actuates an arm 132 which 25 here symbolizes the selector member carried by the box. This occurs at each end of the box stroke. The arm 132 has pawl and ratchet engagement with a wheel 133, which may be any ratchet wheel carried by a friction box and forming 30 part of any type of selector train of connections for selective operation of thread carrier bars.

It makes no difference whether the vertically movable member 131 be a single rod carrying a 35 head 131', or whether it be a composite, such for example as the frame shown in Figure 27, provided the head of the bar or frame have sufficient length parallel to the friction rod to present presser surfaces to the lever 132 at the ends 40 of the stroke, and to cover the range of stoppages at the two ends of the stroke caused by the narrowing operation.

The present invention is applicable generally to the operation of all forms of friction-box-carried 45 selectors which involve movable members, shifted from outside the box, for example, rotary members, whether the rotary members make actual engagement with the selector bars, or rotate cams which shift the positions of operating levers, fingers, or other operating bar-engaging devices.

In order to make this fact clear connection is shown in this application from an actuator which is not movable lengthwise of the machine, not only to the star wheel engaging form of Figures 1, 2 and 8, already described, in which ratchet actuation is given separately to two different ratchet wheel shafts each carrying a star wheel for direct engagement with the bars; but also by 50 the forms of Figures 34, 35 and 36, and Figures 37 and 38 to forms which have been manufactured and commercially used employing ratchet-operated shafts carrying cams for the tilting of levers to engage with and carry the bars; and in 55 Figures 39 and 40 to a single star wheel rotated, step-by-step at each end of the stroke of the box.

The specific forms of actuation of the levers shown in Figures 34-38 from step-by-step actuated cam shafts carried by the friction box are 60 not applicant's own invention and are disclaimed. However, modifications have been made of these devices which have been manufactured and commercially used to cooperate as receiving mechanisms with wholly different actuators than have 65 been used with them, which combinations and

the actuators are claimed herein. The selector form of Figures 39 and 40 is not intended to be claimed in the application, but it is intended to claim herein its combination with the actuator and the actuator itself. 5

In all of the forms the actuator is wholly disconnected from and not carried by the friction box except as, during the operation of the actuator at the two ends of the friction box stroke, the actuator temporarily engages an operating 10 member carried by the friction box. In each case the actuator operates in zones wide enough lengthwise of the friction rod to engage the selector operating member carried by the friction box wherever the operating member may stop, notwithstanding the variation in stopping place due to narrowing. 15

In Figures 34 and 35 are shown any shaft 134 already present in the machine bed 135, the usual carrier rods 136 and the friction rod 137. The 20 slur bar guide 138 and the reciprocating slur bar 139 are shown in dot and dash only, for the purpose of showing normal position of the parts.

The shaft 134 serves merely as a guide here and does not affect the operation. 25

The friction rod 137 is reciprocated by the Coulier mechanism causing it to impart motion to certain carrier rods 136.

The friction box 140 is mounted on the friction rod 137 and is extended at 141 so that it and its 30 strap 142 will be guided by shaft 134 providing free longitudinal movement with respect to this shaft.

The pintle 143 acts as a pivot for three tilting levers or arms 144, 144', 144² mounted in slots 35 145 in the frame and arranged to extend at their outer ends over three carrier bars 136', 136², 136³ which they are selectively and successively to engage and carry. One end of each lever or arm is connected by means of a spring 146 with a 40 fixed part 147 of the friction box and the opposite end of each arm or lever is provided with a latch 148 for engagement with the recess 149 in the lug or dog 150 connected with one of the carrier rods 136. The levers being of different lengths, these 45 latches 148 engage respectively with different dogs upon different bars.

Each of the bars as usual carries a thread-laying arm 151 by which the yarn is laid in knitting position and so arranged that the paths of travel 50 of the yarn delivery ends of these arms are parallel and in close proximity to each other but spaced sufficiently so that each can operate independently of the other.

On each arm 144 the latch 148 is pressed 55 downwardly by a flat spring 152 mounted upon the top of said lever or arm. The latch 148 thus can yield against the pressure of its spring if movement of the latch takes place when the latch is not in line with the recess 149 and when to 60 force the arm downwardly would be to break parts of the arm or dog or to fail properly to connect the latch with its appropriate notch. This protection is afforded, whatever the reason for failure of the latch to correspond in position 65 lengthwise of the bar with the notch into which it is intended to fit. The corners of the latch may be slightly beveled at 153 and the corners of the recesses or notches may be rounded correspondingly at 154 to facilitate this engagement. 70

The pintle 143 is free to swing nearly vertically within the bed 135 through a space in the bed which may be of any shape or character provided it allows bodily swinging movement of the pintle 75 in an arc perpendicular to the axis of the pintle.

This arc path of movement is indicated at 155 and is for the purpose of throwing the entire selector mechanism out of commission by lifting the pivot point for the arms 144, 144', 144" and hence keeping the outer ends of the arms and their latches 148 from engagement within the notches 149 in the dogs 150.

The pintle is guided and swung by a pair of plates 156 (Figures 34 and 35) which carry the pintle at one end of each plate and at the opposite end are keyed at 157 to a shaft 158 by which both plates concurrently are swung upwardly and downwardly as desired. The shaft 158 serves a purpose in cooperation with bolts 159 of holding the side bars 135', 135" rigid with respect to the body, the bolts moreover holding these side frame members tightly against the body.

The shaft 158 has bearing at both ends in the side frame member 135', 135" and is oscillated by lever 160. The shaft 158 carries the plates 156 whose edges 161 are notched at 162 so as to cooperate with an otherwise fixed, longitudinally spring pressed nose 163 to retain the index in either of the two positions of adjustment, the one shown being the position for operation of the selector to carry the thread bars in suitable succession and the other being an inoperative position in which the latches are at all times held too high to reach the recesses 149. The plates 156 operate within suitable slots in the body 135.

This permits disconnection at any part of the three carrier sequence, without matching up with any particular bar.

The arms or levers 144 are adapted to swing about the pintle rod 143 in order to engage and disengage the latches 148 from the lugs 150 upon the carrier bars. For this purpose each arm 144 is provided with an adjustable stud 164 which studs are fitted in correspondingly threaded holes in the arms and are secured therein by lock nuts 165, holding the stud firmly against accidental displacement. Each of the studs 164 is engaged by a different cam wheel 166, 167, 168, having cam projections 169 and intermediate recesses 170.

All of the cam wheels are secured to a shaft 171 so as to rotate with it. Shaft 171 is progressively rotated by step-by-step turning of a ratchet wheel 172 which also is secured to the shaft. The shaft has suitable bearings in the side body members 135', 135", and suitable collars 173 and 174 and hubs 175, 176 and 177 secured to the shafts facilitate fastening of the cam wheels in proper lateral position and proper angular relations to carry out the successive selections of the bars.

The fastening device may be of any suitable character. Set screws 178 are shown.

Connected rigidly with the ratchet wheel or with the shaft to which the wheel is secured is an index disc 179 within whose notches fits a spring 180 pressed ball 180 conveniently located adjacent to the disc in a suitable support on the shaft 171. The purpose of the ball is to hold the disc and hence hold the cam shaft in successive positions to which it is thrown by angular movement of the ratchet wheel. The shaft 171 turns within a bar in a fixed member 181. The spacing of the parts is effected by collar 182. A swinging latch-carrying member 183 is held in place on the shaft by collar 173.

The latch 184 carried by the member or arm 183 is pressed into engagement with the ratchet teeth by a flat spring 186. The spring is held in engagement with the arm by a screw 187. Rigidly connected with the same rocker arm is a second arm 188 which, because it is to be operated in

the present instance by a swinging lever 74 of the same character as seen in others of the figures, extends downwardly into convenient position for its surface 189 to be engaged and thrown by a bar 73⁴.

Because the same swinging lever arm 188 is to be actuated at each end of the stroke of the friction box by the bar 73⁴ it matters not whether the bar 73⁴ be a straight bar extending from one presser face position to the other or not, as this structure does not take advantage of any depression or space between the presser faces. This requires only that there be presser faces in position to engage it at the two ends of the stroke. Each presser face must be long enough (in the direction of movement of the friction box) so that the lever 188 will be engaged at each end of the friction box stroke notwithstanding variations in stopping position due to narrowing operations.

The rocker shaf including the spring pressed 20 pawl and the lever 188 is retracted after each actuation by any suitable spring 190 extending between it and a fixed bar 191.

The operation of the presser bar 73⁴ therefore does not even require that there be a recess or 25 depression between the two presser faces. As in the case of Figures 26, 27 and 28, the mechanisms presenting the two presser faces can be connected or independent as desired.

The angular positions of the three cams are so 30 staggered with respect to the positions of the studs that successive actuations of the lever arm 188 and successive angular advances of the shaft result in engagement of the appropriate lever latches one at a time with corresponding thread 35 carrier bars so as to carry out the same function of laying individual courses, of threads successively from different yarn sources as in the case of the form shown in Figures 1-28. When it is desired not to use the selector mechanism illustrated and described, the lever 160 is operated to lift all of the operating latches to high for use to engage their respective bars and the flat knitting machine is left free for operation using other thread carrier bars just as would have been the 45 case if no selector mechanism had been provided.

The direction of operation of the actuator mechanism can, of course, be varied as in the case of the other figures with the purpose and effect however that the receiving member carried by the friction box is in position at each end of its stroke to be engaged by an actuator which does not travel with the friction box and which delivers its impulse in a direction transverse to that of friction box movement. It will be obvious 50 that the character of the receiving member carried by the friction box as well as that of the presser bar of the actuator may be varied greatly, provided they be adapted in position and movement, one to the other.

The structure of Figures 37 and 38 bears considerable resemblance to that of Figures 34, 35 and 36 with a slightly different application to the levers of the selector. In these views the friction rod is shown at 192 supporting a friction box 65 193 which is guided and prevented from rotation about the friction rod by any suitable guide rod or bar 194 along which the guide casing 195 of the box slides in normal operation. Here as in Figures 34, 35 and 36, the friction material carried by the friction box has not been illustrated. It will be understood that any convenient method of applying this friction and releasing it when it is not required, may be used.

The friction box 193 in its upper part 196 sup- 75

ports and gives bearing for a shaft 171' carried by the box and about which three levers 197, 198 and 199 may tilt, under the influence of three cams 200, 201 and 202 each splined to the shaft 5 171' as at 203. The levers are held in engagement with their respective cams by springs 204, 205 and 206 and the cams are spaced along the length of shaft 192 in agreement with the spacing of the levers, and lie in different angular relations 10 about the shaft 192 so as to operate the levers in the desired sequence with the force and effect that, one at a time, the ends 207, 208 and 209 of the lever arms are forced into the recesses 210, 211 and 212 of lugs 213 carried by bars 214, 215 15 and 216.

Since the entry of the ends of the levers into the recesses of these lugs is brought about by springs causing the levers to follow up the cams but positively releasing rather than positively engaging, the springs give protection against improper forcing of the lever ends where the lever ends fail to match up accurately with the respective recesses into which they are intended to fit.

25 The fact that the levers are held against the cam projections 217 and within the cam recesses 218 by the springs makes it possible to render all of the levers ineffective and the selector device inoperative by the very simple expedient of securing a plurality of engaging fingers (stops) 219 to turn with the shaft 220 and turning this shaft by a handle 221 so that the fingers 219 press against the portions 222 of the levers and effectively render these levers inoperative.

30 The ratchet wheel 223 is splined to shaft 171' so that rotation of the ratchet wheel step-by-step will rotate the shaft correspondingly and will carry with it the several cams by which the levers 197, 198 and 199 are controlled.

40 Freely swinging about the shaft 171' is a rocker arm 225 whose arm 226 carries a pawl 227 pivoted at 228. The pawl is pressed to its duty resiliently by a spring 229 held in place by a screw 230.

45 The second arm 231 of the rocker arm lies within the path of movement of a lever arm 74° which is or may be of the type of lever 74 and its various modifications shown in the previous figures. In direction of movement it will be noted that lever 74° operates in the direction shown in 50 Figures 32 and 33, opposite to that in the other figures. This movement (as contrasted to that in Figure 26) is here secured by placing the swinging arm 77 between the cam wheel and arm 74° so that link 76' becomes a thrust member and not a tension member. Spring 103 is therefore attached to the lever 74° above its pivot point 76'. Arm 77 can be slid on its pivot as in Figure 26.

55 Arm 231 is retracted by a spring 232.

With engagement of the lever 74° with the rocker arm lever 231 the rocker arm is thrown to the right of this Figure 37 with the result that the ratchet wheel and the shaft 171' are turned 60 in counterclockwise direction (in the figure) so that the cams carried by the shaft successively operate the selector levers.

The selector levers 197, 198 and 199 in turn engage and operate the several thread carrying bars 214—216 in any order predetermined by the formation and relation of the cams.

65 Since actuator lever 74° engages the same selector lever 231 at each end of its stroke it is again immaterial as to the detail of the actuator bar or bars by which pressure is brought to bear

upon lever 231 at the two ends of the stroke, provided that appropriate presser surfaces are available at these two ends, extending far enough in length in the direction of the movement of the carriage to be in position to operate lever 231 at each end of the stroke notwithstanding the variation in the length of stroke due to narrowing. This device of Figure 37 therefore is capable of successively laying single courses of thread from the sources represented by the three different thread bars, the function secured by the structures of Figures 1-29 and 34-36 and more particularly detailed in connection with the earlier figures.

70 I have intended the various structures to show different types of selector operating mechanisms in order that the illustration may make clear that the present actuator is capable of setting in motion a considerable variety of selectors. This is true whether the selector require separate actuation of different mechanisms at the respective ends of the stroke, as in the case of the two star wheels of Figures 1 to 8, or involve the operation of fingers all lifted and allowed to lower by the same selector operating mechanism 75 as in Figures 34 and 35 and in a different form in Figures 37 and 38, or provide actuation of a single star wheel mechanism as illustrated in the figures about to be described. These various figures are taken as typical of divergent force, all actuated by the same form of actuator.

In Figures 39 and 40 a form of selector is shown which is more nearly comparable with the form of Figures 1 to 8 than with the form of Figures 34 to 38 since it uses a star wheel for 80 movement of the bars.

The friction box frame 233 is mounted upon the friction rod 234 to move with it and is guided by a separate rod or bar 235.

The connection with the friction rod is through 85 suitable leather or other friction devices which may be of any accepted type and which are not described here, the complete assemblage forming a friction box adapted to engage bars 1, 2 and 3 and carry them until they engage with suitable 90 stops, after which the friction rod slides through the friction box as in the other forms.

The frame 233 is held to its duty in slide engagement with bar or rod 235 by a removable plate 236 secured by bolt 237. When the plate 95 is removed the frame of the device can be swung about the friction box to prevent operating engagement with the thread carrier bars.

The device is very simple. It comprises a single star wheel 238 having engaging prongs 238', 238², 238³ and 238⁴ and 238⁵, spaced at such a distance that the movement from a position having any prong engaging the lug 239, 239' or 239³ of a bar to 1, 2 or 3 position where the next prong engages the same lug of the same bar represents three 100 actuations of the star wheel, i. e., corresponds, angularly, with three teeth 240 of a ratchet wheel 241.

The ratchet wheel and star wheel are rigidly secured together and rotate about or upon a suitable shaft 242 fixed in the frame. The star wheel is apertured at 243 presenting hollows on the face toward the frame 233 which hollows successively receive ball 244 pressed by spring 245 within the frame, the other end of the spring being retained 105 by a plug. The spring pressed ball retains the star wheel in its successive positions against accidental turning.

About the same axis as that of the shaft mounting the star wheel and ratchet wheel and permis- 110

sibly about or upon the same shaft 242 oscillates a rocker arm 246 held in position by a nut 247. At the outer end of the rocker arm are pivoted the latch 248 engaging with teeth 240 and a connecting link 249 through which the rocker arm is oscillated by lever 250. The connection of the lever with the link is through a pin 251 in the lever and slot 252 in the link. The parts are held together by a spring 253 engaging the link at one end at 254 and a pin 255 at the other end, the pin 225 being secured to the lever 250. The pintle is off center with respect to the length of the link as in the case of the structure illustrated in Figures 1, 3 and 3a, so that the spring 253 not only normally holds the pin in its slot but, after each operating pull on the link lug, returns the parts to position for a new actuation.

The arm 250 is pivoted at 256 and extends beyond the pivot at 257 for engagement by an actuator presser member 74¹⁰. The actuator presser 74¹⁰ may be of any type not permanently connected but momentarily engaging and actuating the selector member. Its form and direction and extent of movement will of course be determined in large measure by the form, direction and extent of movement of the selector member, here extension 257. Because this arm is downwardly directed the form illustrated is of the swinging arm variety.

Since there is a single arm 257 only to be operated, and since this is the same arm at each end of the stroke of the friction box, the presser faces for actuation at the two ends of the stroke may be part of a continuous presser bar or may have any intermediate form desired, providing the two presser faces be presented properly to the arm one at each end of the stroke.

As will be seen successive actuations of the star wheel will bring the different prongs of the wheel into engagement in turn successively with the lugs of the three thread carrier bars.

It will be evident that the different forms of the selectors illustrated, but not separately claimed herein, present their own advantages of completeness, simplicity and lack of expense, etc.; but of whatever form they are all capable of operation by an outside actuator which does not move parallel with the line of movement of the friction box, which operates in a direction transverse to the direction of friction box travel, and their engagement with the proper operating member carried by the friction box is limited to the actuation time at each end of the stroke.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention what I claim as new and desire to secure by Letters Patent is:

1. In a flat knitting machine having a cam shaft, a friction rod, friction box and carrier bars, a single star wheel carried by the friction box for automatically and selectively directly engaging and disengaging the carrier bars for movement of the bars, a shaft for the star wheel, a ratchet wheel on the shaft, a pawl and pawl arm for turning the ratchet wheel and an actuator for the arm normally free from engagement with and support by the friction box, movable in a direction transverse to the direction of movement of the friction

box and engaging the arm at each end of the stroke of the box.

2. In a flat knitting machine having a cam shaft, a friction rod, friction box and carrier bars, a star wheel selector mechanism and connections carried by the friction box and capable of being actuated from outside the friction box and an actuator fixed against movement longitudinally of the machine, normally wholly disconnected from the friction box and parts carried by it adapted at the ends of the friction box stroke to operate the selector.

3. In a flat knitting machine having a cam shaft, a friction rod, friction box and carrier bars, a pair of star wheels each separately engaging with the carrier bars in turn, ratchet operating mechanisms, one for each star wheel, separately engaging the star wheels to operate them and each terminating in an operating arm and means, normally disconnected from the arms, movable in a direction transverse to the direction of movement of the friction box and adapted to engage the arms, one at a time, at the respective ends of the friction box stroke.

4. In a flat knitting machine having a cam shaft, a friction rod, friction box and carrier bars, a pair of star wheels each separately and positively engaging with the carrier bars in turn, ratchet operating mechanisms, one for each star wheel, separately engaging the star wheels to operate them, and each terminating in an operating arm, and actuating means swinging toward and away from the operating arms in a direction transverse to the direction of movement of the friction box for engaging the arms at intervals, one at a time, at the respective ends of the friction box stroke.

5. In combination with a friction rod, friction box, carrier bars and cam shaft of a full-fashioned knitting machine, mechanism for automatically and selectively engaging and disengaging carrier bars for the operation of the bars, all mounted upon and travelling with the friction box, the mechanism including separate star wheels and ratchet actuating means therefor, and an actuator normally disconnected from the friction box, movable in a direction transverse to the path of movement of the box and separately engaging the ratchet operating means, one at one end of the stroke and the other at the other end of the stroke to separately actuate the star wheels to shift one star wheel when the bars are held by the other star wheel.

6. In a selective drive for the thread-carrier bars of a flat knitting machine, a friction rod, means for reciprocating the same, a friction box for the rod, a latch actuating arm carried by the box, a pawl carried thereby, a ratchet wheel operated by the pawl, a shaft therefor, a star wheel carried by the shaft, means for retaining the star wheel in successive set positions, thread-carrier bars, means for supporting the bars for reciprocation, engaging devices carried by the bars with which the star wheel engages selectively, longitudinally fixed rocking means for shifting the pawl actuating arm, engageable therewith at both ends of its stroke, and circumferentially movable means for operating the longitudinally fixed rocking means.

7. In combination with the friction rod, friction box, carrier bars and cam shaft of a full-fashioned knitting machine, selector mechanism for automatically and selectively engaging and disengaging the carrier bars for the operation of the bars, all mounted upon and traveling with the friction box, a swinging arm and pattern

chain means operated by the cam shaft, including an operating device normally free from engagement with the friction box and with its selector mechanism, movable in a direction transverse to the line of travel of the friction box and engaging the selector mechanism at each end of the friction box stroke to actuate the selector mechanism.

8. A friction-box-carried selector mechanism 10 for flat knitting machines, comprising a plurality of tilting levers adapted to engage thread carrier rods, a common pivot therefor, selective rocking mechanism for the levers, and tilting means for lifting the common pivot to render all 15 of the tilting levers inoperative.

9. In a flat knitting machine having a cam shaft, a friction rod, friction box and carrier bars, selector means carried by the friction box and including a tension spring retracted lost 20 motion connection for engaging successive bars in turn and an actuator therefor comprising a cam carried by the cam shaft, an actuator lever mounted for swinging movement, and means engaged by the cam and swinging the lever to cause 25 engagement of the lever with the selector means.

10. In a flat knitting machine having a cam shaft, a friction rod, friction box and carrier bars, selector means carried by the friction box 20 for engaging successive bars in turn and including star wheel engaging devices and lost motion spring retracted connections therewith, and an actuator therefor comprising a pattern chain driven by the cam shaft and an actuating lever controlled by the pattern chain, said lever engaging and operating the selector means at each 25 extremity of the friction box stroke.

11. In a flat knitting machine having a cam shaft, a friction rod, friction box and carrier bars, selector means carried by the friction box 40 for engaging successive bars in turn and an

actuator therefor comprising a pattern chain, a sprocket wheel upon the cam shaft, carrying the sprocket chain, an idler wheel supporting the sprocket chain, buttons on the pattern chain, a clutch automatically coupling the sprocket 5 wheel to the main shaft or disengaging it therefrom with longitudinal movement of the main shaft, and lever means operated by the pattern chain buttons normally disengaged from the selector means, and thrown into engagement with it to operate it at the ends of the friction box stroke.

12. In a flat knitting machine having a cam shaft, a friction rod, friction box and carrier bars, selector means, including separate rocker 15 arms, separate ratchet mechanisms at the respective ends of the stroke and star wheels adapted to engage carrier bars, all carried by the friction box for engaging successive bars in turn and an actuator therefor comprising a cam carried by the cam shaft, a rocker arm, connections between the rocker arm and the cam whereby it is rocked through engagement by the cam and means carried by the rocker arm for engagement with the selector means, said means being 20 normally disengaged from the selector means but causing engagement between the two at each end of the friction box stroke.

13. In a flat knitting machine having a cam shaft, a friction rod, friction box and carrier bars, selector means carried by the friction box 20 for engaging successive bars in turn, terminating in levers, a separate lever at each end of the friction box and each lever connecting to separate selector mechanism and a rocking arm 25 actuator having engaging faces at opposite ends spaced at a greater distance than that between the two levers, whereby one lever is operated and the other is not operated, alternatively at each end of the stroke.

FREDERICK C. GOOD.
